[57] **CLAIM**

The ornamental design for an electronic-trip, molded-case circuit breaker, as shown and described.

DESCRIPTION

FIG. 1 is a top perspective view of an electronic-trip, molded-case circuit breaker showing our new design; FIG. 2 is a front elevational view thereof; FIG. 3 is a right end elevational view thereof; FIG. 4 is a left end elevational view thereof; FIG. 5 is a top plan view of an electronic-trip, molded-case circuit breaker showing our new design on an enlarged scale; and

FIG. 6 is a bottom plan view thereof. The broken line showing is included for the purpose of illustrating environmental elements only and forms no part of the claimed design.

FIG. 1

FIG. 3

FIG. 4

FIG. 2
